UNITED STATES PATENT OFFICE

118,184

DESIGN FOR A TRAILER

Michael Antimo Zalimeni, Ashtabula, Ohio

Application September 9, 1939, Serial No. 87,102

Term of patent 14 years

To all whom it may concern:

Be it known that I, Michael Antimo Zalimeni, a citizen of the United States, residing at Ashtabula, in the county of Ashtabula and State of Ohio, have invented a new, original, and ornamental Design for a Trailer, of which the following is a specification, reference being had to the accompanying drawing, forming a part hereof, wherein:

I claim:

The ornamental design for a trailer, substantially as shown.

MICHAEL ANTIMO ZALIMENI.
